UNITED STATES PATENT OFFICE

GLEN J. ARTHUR, OF ROCK ISLAND, ILLINOIS

DESIGN FOR A NURSERY CHAIR

Application filed November 14, 1929. Serial No. 33,443. Term of patent 14 years.

To all whom it may concern:

Be it known that I, GLEN J. ARTHUR, a citizen of the United States, residing at Rock Island, in the county of Rock Island and State of Illinois, have invented a new, original, and ornamental Design for a Nursery Chair, of which the following is a specification, reference being made to the drawing, forming a part thereof.

In the drawing Fig. 1 is a side elevation; Fig. 2 is a front elevation; Fig. 3 is a perspective of the article showing my new design.

I claim:

The ornamental design for a nursery chair as shown.

GLEN J. ARTHUR.
